UNITED STATES PATENT OFFICE.

GEORGE F. MOOREHEAD, OF DES MOINES, IOWA, ASSIGNEE TO C. L. PERCIVAL COMPANY,
OF DES MOINES, IOWA, A CORPORATION OF IOWA.

REFRIGERATOR SHOW-CASE.

1,227,922.

Specification of Letters Patent. Patented May 29, 1917.

Application filed May 18, 1912. Serial No. 697,043.

To all whom it may concern:

Be it known that I, GEORGE F. MOOREHEAD, a citizen of the United States, residing at Des Moines, in the county of Polk and State of Iowa, have invented a certain new and useful Refrigerator Show-Case, of which the following is a specification.

The object of my invention is to provide a refrigerator show case of simple, durable and inexpensive construction whereby cold air from ice, or the like may be carried to different parts of the show case and the circulation established past the ice and to the extreme ends of the case.

15 A further object of my invention is to provide a refrigerator show case of convenient construction for displaying goods which must be kept at a low temperature and provided with display shelves so constructed that a circulation of cold air may be easily maintained about all of the goods in the show case.

20 A further object is to provide such a refrigerator show case with detachable parts which may be readily removed for cleaning or repairing.

25 My invention consists in certain details, in the construction, arrangement and combination of the various parts of the device, whereby the objects contemplated are attained, as hereinafter more fully set forth, pointed out in my claims and illustrated in the accompanying drawings, in which:

30 Figure 1 shows a front elevation of a refrigerator show case embodying my invention.

35 Fig. 2 shows a rear elevation of same.

Fig. 3 shows a central, longitudinal, vertical, sectional view through a show case embodying my invention.

40 Fig. 4 shows a perspective view of the detachable false bottom of a show case, and

Fig. 5 shows a perspective view of the detachable shelf and the manner in which the same is mounted.

45 In the accompanying drawings, I have used the reference numeral 10 to indicate generally the frame of my improved refrigerator show case. The front of the device is made of glass 11 preferably in panes spaced apart from each other. At the end of the device are panes of glass 12 spaced apart from each other to leave an air space. The bottom of the device is made of a lower portion 13 and an upper portion 14 spaced apart from each other. In the center of the

refrigerator show case is an ice compartment 15. The top of the ice compartment is composed of two members 16. The top of the show case, excepting over the ice compartment, is composed of glass panes 17 and 18 spaced apart from each other and the pane 19 is inclined slightly downwardly from the top of the ice compartment to the end of the device, as shown in Fig. 3.

50 I provide vertical end members 20, horizontal end members 21 and horizontal side members 22 at the top and bottom of the device to give strength and rigidity to the show case. The ice compartment 15 is provided with a perforated bottom 23 below which is a compartment 24. The water from the ice drips into the compartment 24, from which it passes through a discharge pipe 25. On each side of the ice compartment 15 are display compartments which are constructed alike on each side. I will describe the display compartments on one side of the ice compartment: In the display compartment is a false bottom constructed 55 as follows: A horizontal bottom 26 is supported upon vertical side members 27, as shown in Figs. 3 and 4. The bottom 26 extends approximately half the distance from the ice compartment to the other end of the display compartment. A second false bottom comprising the bottom proper 28 resting upon the vertical members 29 extends from the bottom 26 to the outer end of the display compartment. In the bottom 26 are 60 transverse openings 30 and 31 for permitting air to pass from below said bottom into the display compartment. In the bottom 28 is a transverse opening 32 adjacent to the bottom 26 and a plurality of transverse openings 33 adjacent to the outer end of the display compartment. The compartment 24 communicates with the compartment formed between the bottom 26 and the member 12. It will thus be seen that a 65 passage is formed from the lower part of the ice compartment along the lower part of the display compartment having the openings 31 and 32 and the plurality of openings 33. The upper end of the ice compartment communicates with the upper end of the display compartment through an opening 35, which is somewhat larger than the opening from the compartment 24 to the space between the bottom 14 and the 70 false bottoms of the display compartment.

75 In the back of the refrigerator show case,

110

I provide a door 36 for the ice compartment and a door 37 for the display compartment. It will be noted that the false bottoms in the display compartment may be readily re-
5 moved through the door 37. In the back of the display compartment, I provide a mirror 38 on the door and mirrors 39 on each side of the door 37.

In the display compartment, I preferably 10 provide a shelf of perforated material constructed as follows: At the back of the display compartment at each end thereof at a suitable height, I provide hooks 40. Similar hooks are provided on the front of the 15 display compartment at each end thereof and arranged at the same height as the hooks 40. I provide angle bars 41 provided with perforations to receive the hooks, which angle bars are hung on the hooks in 20 horizontal position, as shown in Figs. 3 and 4. Resting upon the angle bars are trans-
verse bars or rods 42 and resting upon the rods 42 is a shelf 43 preferably made of perforated material such as stiff wire screen.

25 The practical operation of my improved refrigerator show case is as follows: Ice 44 is placed in the ice compartment through the door 36. The ice rests upon the per-
forated bottom 23. The drippings from the 30 ice pass through the bottom 23 into the compartment 24 and are discharged through the opening 25. A circulation of cold air is es-
tablished in the direction indicated by the arrows in Fig. 3. The air passes into the 35 compartment 24 and then into the compart-
ment 27 and into the compartment under the false bottoms in the display compartment. A part of the air passes upwardly into the display compartment through the openings 40 30, 31 and 32. The larger part of cold air passes to the outer end of the device and through the openings 33 into the display compartment. The air rises as it is warmed 45 and passes along the member 19 and through the opening 25 into the ice compartment 15. The member 19 is inclined, as above de-
scribed, to aid in establishing the circula-
tion.

The advantages of my device lie in its pe-

culiar construction whereby the cold air is 50 evenly distributed in the display compart-
ments by means of the arrangement and po-
sitions of the openings 30, 31, 32 and 33, 55 whereby part of the air is permitted to pass
into the display compartment at various
points in the bottom thereof while a large
part of the cold air is carried to the outer
end of said compartment. Articles placed at
any point in the display compartment are
thus subjected to the circulation of cold air. 60

I claim as my invention:

1. A refrigerator show case comprising a central transverse ice chamber having open-
ings on each side at the top and bottom 65 thereof, a cooling chamber in each end hav-
ing the top inclined downwardly from the
end adjacent to the ice chamber and from
a line above the upper edge of the upper
opening in the ice chamber, and a false bot-
tom in the cooling chambers spaced above 70 the real bottom and the top of the lower
opening from the ice chamber, said false
bottom being provided with a series of open-
ings which are graduated to increase in size
or numbers per yard as the distance from 75 the ice chamber of the successive openings
increases.

2. A refrigerator show case comprising a central transverse ice chamber having open-
ings on each side at the top and bottom 80 thereof, a cooling chamber in each end hav-
ing the top inclined downwardly from the
end adjacent to the ice chamber and from a
line above the upper edge of the upper open-
ing in the ice chamber, and a removable sec- 85
tional false bottom in the cooling chambers
spaced above the real bottom and the top of
the lower opening from the ice chamber, said
false bottom being provided with a series of
openings which are graduated to increase in 90
size or be closer together as the distance of
the successive openings from the ice chamber
increases.

Des Moines, Iowa, March 20, 1912.

GEORGE F. MOOREHEAD.
